UNITED STATES PATENT OFFICE

EMMETT M. TUCKER, OF SACRAMENTO, CALIFORNIA, ASSIGNOR TO TUCKER DIESEL MOTOR CO., LTD., A CORPORATION OF CALIFORNIA

TWO-CYCLE GAS ENGINE

Application filed June 23, 1930. Serial No. 463,156.

This invention relates to gas engines, and particularly to one of the so-called well known two cycle type.

The principal objects of my invention are 5 to provide an engine of this general character in which perfect scavenging of the products of combustion is obtained, and the fresh charge is consequently not diluted or contaminated as is ordinarily the case; one in 10 which said fresh charge is highly compressed before being fired, and in which it is not necessary to rely on the crankcase to obtain such compression; and one in which the heated parts are automatically subjected to a cooling action with the operation of the engine. As a result of these features an extremely efficient fuel mixture is attained, the engine 15 itself is extremely efficient and economical to operate; it is much easier to attain and hold the desired compression than is the case with the ordinary two cycle engine, and it is also easier to keep the engine in a proper relatively cool condition than the usual engine of the high compression type.

20 A further object of the invention is to produce a simple and inexpensive device and yet one which will be exceedingly effective for the purpose for which it is designed.

These objects I accomplish by means of 25 such structure and relative arrangement of parts as will fully appear by a perusal of the following specification and claims.

In the drawings similar characters of reference indicate corresponding parts in the 30 several views:

Fig. 1 is a side elevation of my improved engine, built in a single cylinder form, showing the piston in position to receive a power impulse.

40 Fig. 2 is a fragmentary sectional elevation of the engine with the parts in the same position as in Fig. 1.

Fig. 3 is a fragmentary sectional plan on the line 3—3 of Fig. 2.

45 Fig. 4 is a transverse vertical section of the engine showing the piston in a gas discharging position.

Fig. 5 is a side elevation of the engine, showing the cylinder and piston unit inverted relative to the crankshaft.

Referring now more particularly to the characters of reference on the drawings and particularly at present to Figs. 1 to 4, the engine comprises an upper intake and compression cylinder 1, open on its lower end, and a 55 hollow cylindrical head 2 longitudinally aligned with said cylinder and disposed just below said open end. At this end the cylinder is provided with an annular outwardly projecting exhaust manifold 3 which communicates with the cylinder area all around the same, and having a lateral outlet 4 adapted for connection to an exhaust pipe of suitable character. Though the cylinder and manifold have been shown as separate parts this is 60 for convenience of manufacture and they may be considered as a single unit.

Slidably mounted on the head 2 and so as to have a running fit with said head and with the interior of the cylinder (except toward 70 the upper end of the latter where the running fit is relieved) is a sleeve piston or cylinder piston 5, which is closed on its end between the head of the cylinder and the adjacent end of the head, and is movable between these parts to within close distances of the same. Rings 6 above and below the manifold opening and similar rings 7 about the upper end of the head engage the outer and inner surfaces of the piston respectively 80 and prevent leakage of gases therewith.

The piston has circumferential ports 8 adapted to register with the manifold only when the head of the piston is at the top of its stroke or adjacent the head of the cylinder. The head of the piston has a downwardly or inwardly opening valve 9 of the poppet type, which is normally held closed by a spring 10. The cylinder head preferably has a longitudinally adjustable pin 11 which 90 is in the form of a set screw and is adapted to engage and positively depress the stem of the valve if necessary to effect the opening of the latter when the piston is in said position. The head 2 is provided with an ignition plug 12 of common character whose points are exposed to the area A which is between the upper end of the head 2 and the head of the piston. This plug is mounted 95 in a pocket 13 which is open to and down one 100

side of the head and is separated from the hollow interior of the same. This arrangement permits the necessary access being had to the plug, and to the current carrying cable

5 14 connected thereto, from said side of the head when the piston is at the upper end of its stroke and is clear of the pocket as shown in Fig. 4.

10 A fuel-mixture intake pipe 15, adapted at its outer end for connection to a carbureter, extends under the head 2 and then upwardly into the same to near the top thereof, being open at its upper end. At the bottom of the head (which is closed) and to one side of the 15 pipe 15, an outlet passage 16 communicates with a vertical pipe 17 which extends upwardly along one side of the engine and is connected at its upper end to a passage member 18 which in turn communicates with the cylinder 1 on the corresponding side of the engine and adjacent the top of said cylinder. A normally closed poppet valve 19 opening 20 inwardly or toward the cylinder is mounted in the passage 18.

25 The length of the piston is such that when at the upper end of its stroke, its lower end projects below the manifold 3 a sufficient distance to afford proper support for opposed trunnions 20. Said piston at this time 30 of course also still engages the head rings 7. Turnable on the trunnions are the adjacent ends of a forked connecting rod 21 which at its lower end engages the pin of the crank 22 of a crankshaft 23. The throw of 35 the crank is designed so as to cause the piston to be reciprocated through a stroke of sufficient length to move the piston head from adjacent the head of the cylinder to adjacent the upper end of the head 2. The cylinder and head are maintained rigid and in 40 spaced relation to each other by side rods 24 which project through and are securely clamped by nuts 25 to base bosses 26 projecting from said members; while said rods 45 extend down to and support the bearings 27 of the crankshaft.

50 The lower ends of said rods may also serve as the studs for locating and securing the caps of said bearings in place. The particular form of connection between the rods and the cylinder bosses enables said cylinder to be adjusted vertically relative to the head, thereby altering the compression space in said cylinder, as may be desired. The engine as a 55 whole is supported from a suitable foundation by legs 28 which are connected to the rods 24 intermediate the ends of the same. This arrangement is particularly intended for light engines, larger ones possibly needing a different and more rigid structure.

60 The head rings 7 and the inner walls of the piston are lubricated by means of an oil passage 29 extending from the ring grooves to the lower end of the head for connection to 65 a pressure feed pipe 30. The rings 6 and

the outer walls of the piston are lubricated from oil vapors in the fresh mixture which is admitted to the cylinder 1, as is customarily done in two cycle practice.

70 In operation with the piston positioned as in Fig. 2, the firing and expansion chamber A of the cylinder-piston is filled with a compressed charge, which is exploded by the plug, thus driving the piston upwardly and of course imparting rotation to the crankshaft. 75 When the piston reaches the top of its stroke the ports 8 register with the exhaust manifold and the products of combustion rush out. At the same time the valve manifold 9 opens, either by engagement with the pin 11 or by 80 reason of the pressure of the fresh charge in the cylinder above the piston, and which has been highly compressed by the upward movement of the piston. The fresh charge rushing into the chamber A of course positively forces the remainder of the products of combustion into the exhaust manifold and a thorough scavenging of said chamber is thus effected. As soon as the piston starts on its 85 downward stroke the ports 8 move out of register with and shut off the manifold, and the valve 9 closes, and a recompression of the fresh mixture taken into the chamber A, as above stated, now begins. At the same time the downward movement of the piston induces 90 a tendency to vacuum in the cylinder above, causing the valve 19 to open and a rush of fresh mixture to enter the cylinder, to be again compressed upon the subsequent firing stroke and upward movement of the piston. 95 The fact that the cylinder is of course of greater area than the chamber A, and that practically the entire charge from said cylinder is received into the chamber, causes the 100 recompressing action to give the mixture a higher pressure than it had when initially compressed in the cylinder.

105 The fresh charge being first discharged into the head 2 against the top wall of the same before being delivered to the cylinder, not only exerts a beneficial cooling effect on the walls of the head, but by absorbing a corresponding amount of heat is delivered into the cylinder in a properly preheated condition. This arrangement also causes a thorough mixing of the air and fuel to be effected before 110 said mixture is passed to the cylinder; and a further mixing is effected by reason of the alternating compressing and expanding action to which the mixture is subjected before being finally fired. The piston is readily kept in a cool condition by means of a suitable air blast, without any additional mechanism being necessary, since on every alternate stroke, the piston is exposed for the greater 115 portion of its area to the outside of the cylinder.

120 In the engine shown in Fig. 5 the cylinder and piston arrangement remains the same as above described, but they are disposed in in- 130

verted relation to the crankshaft 23a. The connecting rod 21a therefore which is connected to the piston 5a extends downwardly past the cylinder 1a to its connection with the crankshaft. Also the tie rods 24a are placed in position as well as the supporting legs 28a. Otherwise the parts of the engine are unchanged and the movements and functioning of these parts are identical with that described in connection with the first type.

In either case, the piston, being capable of being readily cooled, is not subject to such expansion as is ordinarily the case, and it may therefore have a closer fit with its co-operating parts. This feature, together with the fact that the piston is guided both on the outside and inside, will eliminate piston slap.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a two-cycle gas engine having a cylinder open on one end, a cylindrical head alined and fixed with and extending beyond the cylinder from the open end thereof, and a sleeve piston slidably engaging the head and cylinder and closed on that end which is within the cylinder; an ignition plug mounted within the head in a position to fire a charge confined in the piston, and a pocket in and open to one side of the head and in which the outer end of the plug is disposed; the piston being arranged to uncover said pocket when the piston is moved so that its head is adjacent that of the cylinder.

45 2. In a two-cycle gas engine having a cylinder open on one end, a cylindrical head alined and fixed with and extending beyond the cylinder from the open end thereof, and a sleeve piston slidably engaging the head and cylinder and closed on that end which is within the cylinder; an enclosed chamber formed within the head, a fuel-mixture pipe leading into said chamber and terminating in an open end facing the end of the head which is nearest the head of the piston, and an outlet pipe from the opposite end of the chamber, the cylinder having an intake passage with which said outlet communicates.

60 3. In a two-cycle gas engine having a cylinder open on one end, a cylindrical head alined and fixed with and extending beyond the cylinder from the open end thereof, and a sleeve piston slidably engaging the head and cylinder and closed on that end which is within the cylinder; one end of the piston

projecting at all times in the clear beyond the open end of the cylinder, opposed trunnions projecting outwardly from said one end of the piston, a crankshaft having a single crank thereon disposed centrally of the axial line of the piston, and a forked connecting rod engaging said crank and the trunnions.

4. In a two-cycle gas engine having a cylinder open on one end, a cylindrical head alined and fixed with and extending beyond the cylinder from the open end thereof, and a sleeve piston slidably engaging the head and cylinder and closed on that end which is within the cylinder, exteriorally located circumferentially spaced elements connected to the cylinder and to the head at the end of the latter furthest from the cylinder to tie the two together, one end of the piston projecting at all times in the clear beyond the open end of the cylinder, and connecting rod arms engaging said end of the piston on the outside of the same and projecting beyond the head between the elements.

5. In a gas engine having a cylinder open on one end, a cylindrical head alined and fixed with and extending beyond the cylinder from the open end thereof, and a sleeve piston slidably engaging the head and cylinder and closed on that end within the cylinder; a fuel intake passage leading into the cylinder at its closed end, an inwardly opening intake valve in the closed end of the piston, and means to positively open said valve with the movement of the piston to its limit in the direction of closed end of the cylinder.

In testimony whereof I affix my signature.
EMMITT M. TUCKER.
